J. EATON.
MOTOR CONTROL SYSTEM,
APPLICATION FILED APR. 23, 1915.

1,233,854.

Patented July 17, 1917.

UNITED STATES PATENT OFFICE.

JOHN EATON, OF SCHENECTADY, NEW YORK, ASSIGNOR TO GENERAL ELECTRIC COMPANY, A CORPORATION OF NEW YORK.

MOTOR-CONTROL SYSTEM.

1,233,854.

Specification of Letters Patent. Patented July 17, 1917.

Application filed April 23, 1915. Serial No. 28,338.

To all whom it may concern:

Be it known that I, JOHN EATON, a subject of the King of Great Britain, residing at Schenectady, county of Schenectady, 5 State of New York, have invented certain new and useful Improvements in Motor-Control Systems; of which the following is a specification.

This invention relates to the electrical 10 operation of machine tools such as planers and the like, and has for its object the provision of means whereby the operation may be carried out and properly controlled in a reliable, simple and efficient manner.

15 More specifically, my invention relates to the electrical operation of planers, in which in addition to the electric motor for driving the planer there is employed a feed motor for operating the feed mechanism. In 20 the electrical operation of planers, especially the larger sizes, it has been found desirable to employ such a feed motor especially since this motor may also be utilized to rapidly traverse the tool back to its starting position 25 after the cut has been completed in addition to performing its function of feeding the tool. As heretofore employed, the feed motor was of necessity of the reversible type, but I have found that it is possible to dispense 30 with the reversing feature thereby greatly simplifying and improving the apparatus. One of the objects of my invention is to provide a control system in which the feed motor always operates in the same direction.

35 Another object of my invention is to provide means whereby the feeding operation will begin before the main motor stops or at least before it starts in to rotate in the opposite direction. By starting the feed 40 motor before the main motor reverses, a considerable saving of time is effected since the amount of overtravel of the tool which would otherwise be necessary in order to give time for the feeding will be reduced.

45 Another object is to provide means whereby the beginning of the operation of the feed motor depends upon the speed of the main motor, that is, when the speed of the main motor has dropped to a predetermined 50 point the feed motor will be started. Other objects and purposes of my invention will appear in the course of the following specification, in which I have shown my inven-

tion embodied in concrete form for purposes of illustration.

55

In the accompanying drawing illustrating one embodiment of my invention, Figure 1 is a diagrammatic view of a system of motor control embodying my invention; and Fig. 2 is a detail of the feed mechanism of 60 the planer.

The features of the control in so far as the main driving motor is concerned, forms no part of my present invention, the specific system herein disclosed being described and 65 claimed in patent to Murphy and Eaton, 1,041,845. However, in order that the system as a whole may be clearly understood I shall describe the system in general and then point out the features of novelty.

70

Referring to Fig. 1, A represents the armature and F the shunt field of an electric motor for driving a planer or the like. The direction of rotation of this motor is controlled by four electromagnetic switches or 75 contactors, two for each direction of rotation. Two of these switches are designated C and C' respectively, since they connect the motor for driving the planer in the forward or "cutting" direction, while the other two 80 switches are designated R and R' respectively, since when closed they drive the planer in the opposite or "return" direction. These four switches are operated by shunt windings controlled by the master switch S. 85 In the drawing the electromagnetic switches are shown in the positions which they assume when the main line is deenergized and the master switch is shown in its intermediate or off position. When the master switch 90 S is moved to the position *a*, and the line is energized, the windings of the contactors C and C' are energized in series across the line, while with the switch in the opposite position *b*, the windings of the two contactors R and R' are similarly connected across the line.

A starting resistance D is provided for the motor A, this resistance being controlled by an electromagnetic switch 10, connected 100 so as to close and short circuit the resistance when the counter electromotive force of the motor rises to a predetermined value. For varying the speed of the motor, two field rheostats are provided, one of which has a 105 resistance *r* which is controlled by the arm

11, while the other has a resistance r' which is controlled by the arm 12. When the motor is started, the switch 10 is open and both of the resistances r and r' are short circuited 5 through wire 13 and switch 14, which is spring closed. When the switch 10 closes, the switch 14 is opened so as to break the short circuit. When the master switch S is in the position a , that is in the "cutting" 10 position, a portion of the resistance r , the amount of which will depend upon the position of the lever 11, will be connected in the field circuit. When the master switch is moved to the position b , the connection to 15 the arm 11 is broken at the interlock 15 by the closing of the line contactor R'. The field circuit will then be completed through wire 16 so that all of the resistance r and a portion of the resistance r' , depending upon 20 the position of the lever 12, will then be in the field circuit.

In order to bring the motor armature to rest quickly a brake resistance is provided through which the motor armature is short 25 circuited. This brake resistance is composed of two sections BR and B'R'. The purpose of these two sections of resistance is to graduate the dynamic braking current as the motor field builds up and the speed of the 30 motor slows down. For making the braking connection, the contactor B is provided, which is normally closed by a spring 17. The winding of this contactor is connected across the motor armature so that while the 35 motor is operating, the winding tends to close the contacts. This contactor is also provided with a series winding 18, which is not energized until the contactor is closed. The five contactors R, R', C, C', and B being 40 arranged as shown in the drawings, are provided with four mechanical interlocks, 19, 20, 21 and 22, coöoperating with the contactors so as to compel operation in a predetermined manner. While the contactor B 45 is closed by a spring, this spring is not sufficiently stiff to apply any considerable pressure to the contacts, since the two windings are provided for holding the contacts tightly closed.

50 An electromagnetic switch or relay 23, is provided with a winding having one terminal connected with the shunt field winding F, while the other terminal is connected to resistance r . The winding of the relay is 55 divided into two halves which are wound differentially to each other so that when the two halves are energized, they neutralize each other and the relay will not close. It is obvious that when the switch 14 is open, 60 the field current must pass through the two divided portions of the relay winding and through any field resistance which may be in the circuit. The relay is therefore inoperative under this condition. When, however, 65 the switch 14 is closed, the lower half of the

relay winding and the field resistance are short circuited so that one-half of the winding is energized and the relay is operative. The winding of this relay is so adjusted that when the field current approaches a maximum, that is when the field reaches nearly full strength, the relay will close but when the field is weak, the relay will not close even though only the upper winding is energized. When the switch 14 closes, the field resistance 70 is short circuited so as to strengthen the field but the field strength increases only gradually due to the inductive effect. The relay 23 will not operate until the field current rises to a predetermined value, but 75 when it does operate, it short circuits the section of braking resistance B'R'. When the relay 23 closes, to short circuit the braking resistance B'R', it connects in circuit a contactor 24 of the series or current limit type. 80 This type of contactor is now well known and has the property of holding open when the current is high and closing when the current falls to a predetermined value. When, 85 however, the relay 23 is closed and the section of resistance B'R' is short circuited, the braking current will rise to the limit of safety. As the motor slows down, the current will decrease to proper value and series contactor 24 will close and short circuit the 90 other section of resistance BR.

It is to be understood that the master switch S is operated by dogs on the planer so that when the platen of the planer reaches the end of the stroke, the switch S will be 100 thrown from one extreme position over to the opposite position which will stop the motor and start it in the opposite direction. The operation up to this point is the same as that described in the patent above referred to.

For feeding the tool up to the work, I provide a feed motor having armature A' and field F'. The operation of this feed motor is controlled in the first instance by the master switch S, the operation of which initiates the circuit for the feed motor. The feed motor is also controlled by the speed of the main motor so that although the master switch is thrown over, the feed motor will 110 not operate until the main motor speed drops to a predetermined value. This control of the feed motor together with the fact that the motor always operates in the same direction constitute important features of 115 my present invention. The feed motor is stopped after making a predetermined number of revolutions by means of a controller E driven by the feed motor. The feed motor is not controlled directly through the contacts of the master switch S and the controller E, but is controlled by a double throw contactor J having a shunt operating winding 25 which when energized closes the contacts 26 and completes the feed motor 120 130

5 circuit. Contacts 27 when closed makes a dynamic braking circuit for stopping the feed motor. When the winding 25 is deenergized the contacts 26 open and contacts 27 close.

10 As above stated, the feed motor always operates in the same direction instead of operating first in one direction and then the opposite direction as has been the practice heretofore. It is understood of course, that ordinarily the motor will operate the feed upon one operation and on the succeeding operation will operate the ratchet. This is 15 illustrated in Fig. 2 which shows the operation upon the standard feed mechanism of a planer. The feed motor drives the plate 28 first through one half of a revolution and then through the remaining half. During the feed operation, the crank pin 29 will be 20 moved from position 30 to position 31, thereby rotating the feed screw shaft 32 in a clockwise direction by means of a segmental gear 33 and pinion 34 carrying a pawl 35 driving a ratchet wheel on the screw shaft. 25 When the feed motor again operates, the crank pin moves from position 31 to position 30. The feed screw will not now operate since pinion 34 ratchets on the feed screw shaft in a manner well understood. By 30 shifting the pawl the operation will be reversed.

The controller E which is driven by the feed motor limits the rotation of the feed motor so that the plate 28 moves as above 35 described. The motor is stopped by interrupting the circuit at one contact, as for instance at contact 36, the circuit for the next operation being made at contact 37. These contacts 36 and 37 correspond 40 with opposite positions of the master switch, that is when the master switch is in position *a* the feed motor will be started through contact 37 and when it is in the position *b* the motor will be started through 45 contact 36. The feed circuit to the contacts 36 and 37 is through contact 38 which is in permanent engagement with its contact segment and the circuit to contact 38 is either through the contacts on relay 39 50 or through contacts 40 which are closed when the electromagnetic switch J closes. These contacts 40 short circuit the contacts on relay 39, so that after the feed motor circuit is closed, it can not be opened 55 by the relay 39. A double throw switch G serves to place both the main motor and the feed motor in service in one position, while in the other position it connects only the feed motor in circuit for traversing the 60 tool to any desired position.

As thus constructed and arranged, the operation is as follows: Assuming the master switch S to be thrown to the position *a* and switch G thrown to the left, contacts C and C' will close and start the

main motor in the "cutting" direction. When the motor reaches a predetermined speed, starting resistance D is short circuited by the operation of counter E. M. F. relay 10. The closing of the relay 10 opens 70 the switch contacts 14 which weakens the field by opening the short circuit on the field resistance. The field current now passes from the positive side of the line through the contacts 15 of contactor R' 75 through lever 11 and whatever portion of resistance *r* may be in circuit, through the two windings of relay 23 and the field F to the negative side of the line. When the end of the stroke is reached, the reversing 80 switch S will be thrown to position *b*. This will cause the contactors C and C' to open and the brake contactor B, which has heretofore been held open by the mechanical interlock 19, to close, thereby completing 85 the dynamic brake circuit through the brake resistance BR and B'R' and the motor is quickly brought to rest in the manner described in the patent above referred to.

The movement of the master switch to 90 the position *b* also initiates the movement of the feed motor. When the switch is thrown over to the position *b*, connection is made from the positive side of the line through contact 41 to contact 36 on the controller E, thence by wire 42 to the contacts of the relay 39. These contacts are open when the master controller is thrown over to position *b* but closed when the speed of the main armature A drops to a predetermined value. When this speed, which is the speed at which it is desired that the feed motor shall start is reached, the circuit is completed from the contacts of relay 39 through the winding 25 of contactor J to 100 the negative side of the line. The contactor J now closes the contacts 26 and the armature circuit of the feed motor will be completed from the positive side of the line through wire 44 and the contacts of switch 110 G to the switch contacts 26 through the frame of the switch J to starting resistance H and the winding of series contactor 45, armature A' and back to the negative side of the line through 46. As the armature 115 A' speeds up, the starting resistance H will be short circuited by the closing of series contactor 45 and after a predetermined number of revolutions, the feed motor stops because the circuit is opened at contact 36 120 and initiated for the next operation at contact 37. The feed motor will now operate to either feed or ratchet as the case may be. Preferably the feed operation will take place at the end of the return stroke, although in some cases, it will take place at the end of the cutting stroke. It will be noted that the feed motor begins to operate before the main motor stops or at least before it starts to rotate in the oppo- 125 130

site direction. By properly adjusting the relay 39, it can be either made to start practically as soon as the reversing switch is thrown, by having the relay 39 drop when the speed of the main motor is high, or the operation may be delayed until the main motor is nearly stopped.

The reversing switch being now in the position *b* as soon as the main motor stops, contactor R' closes by reason of the opening of the brake contactor B. The motor will now start in the opposite direction and come to speed as before. In this case, however, the speed will be higher since the contactor R' being closed, there will be no circuit through the contacts 15 and the field circuit must pass through wire 16 so that all of the resistance *r* and a portion of *r'* depending upon the position of the lever 12 will be in the field circuit. When the end of the stroke is reached, the master switch will be operated to the position *a* and the motor will be dynamically braked and finally stopped as before. The controller E having been moved by the operation of the feed motor so that contact 37 is now in engagement with the segment instead of contact 36, the feed motor will be started as before. It will also operate in the same direction in which it operated before and this time, will operate the feed screw on the assumption that the feeding is to be done at the end of the return stroke. This operation will continue, the feed motor operating the plate 28 one half a revolution, to either feed or ratchet and, upon the end of the next stroke, operate in the same direction, to either ratchet or feed. The feed motor is brought to rest quickly by a dynamic braking circuit which is closed at the contacts 27 through resistance H and series winding 47. This series winding holds the contacts 27 together until the motor stops, that is, it has the same function as the series winding 18 on the brake contactor B. On throwing the switch G to the opposite position, the feed motor can be caused to operate the feed screw in the opposite direction continuously without the control of the controller E. This is accomplished by energizing the winding 25 of contactor J directly across the line. The circuit of this winding will now be from the positive side of the line through wire 44, contact on switch G, wire 48, winding 25 to the negative side of the line through wire 46. By throwing the master switch S to one position or the other so as to actuate either the contactors C, C' or R and R', the feed motor will be caused to operate in either direction as desired.

What I claim as new and desire to secure by Letters Patent of the United States, is:—

1. The combination of a main electric motor for driving a planer or the like, a re-

versing switch therefor operated by the movement of the planer, a feed motor, means whereby the feed motor is energized for the same direction of rotation each time the reversing switch is operated and means for stopping the feed motor after it has made a predetermined number of revolutions.

2. The combination of a main electric motor for driving a planer or the like, a reversing switch therefor operated by the movement of the planer, a feed motor controlled by the switch and by the speed of the main motor, and means for stopping the feed motor after it has made a predetermined number of revolutions.

3. The combination of a main electric motor for driving a planer or the like, a switch for stopping and reversing the same periodically, a feed motor, means whereby the feed motor is energized for the same direction of rotation each time the reversing switch is operated but before the motor stops so that the feed motor operates before the main motor starts in the reverse direction, and means for stopping the feed motor after it has made a predetermined number of revolutions.

4. The combination of a main electric motor for driving a planer or the like, a reversing switch therefor operated by the movement of the planer, means whereby the motor is dynamically braked, and reversed when the switch is operated, a feed motor, means whereby the feed motor is energized for the same direction of rotation upon each operation of the reversing switch so that the feed motor operates while the main motor is being dynamically braked, and means for stopping the feed motor after it has made a predetermined number of revolutions.

5. The combination of a main electric motor for driving a planer or the like, a switch therefor operated by the movement of the planer, means whereby the motor is dynamically braked and reversed when the reversing switch is operated, a feed motor, means whereby the feed motor is energized for the same direction of rotation upon each operation of the reversing switch when the speed of the motor drops to a predetermined value so that the feed motor starts when the main motor has been braked to a predetermined speed, and means for stopping the motor after it has made a predetermined number of revolutions.

6. The combination of a main electric motor for driving a planer or the like, a switch therefor operated by the movement of the planer, a feed motor, means whereby the feed motor is energized for the same direction of rotation each time the reversing switch is operated, means whereby successive operations of the feed motor cause alternate feeding and ratcheting operations, and means for stopping the feed motor after

it has made a predetermined number of revolutions.

7. The combination of a main electric motor for driving a planer or the like, a switch 5 for stopping and reversing the same periodically, a feed motor, means whereby the feed motor is energized for the same direction of rotation when the reversing switch is operated and the speed of the main motor reaches 10 a predetermined value, and means for stopping the feed motor after it has made a predetermined number of revolutions.

8. The combination of a main electric motor for driving a planer or the like, a switch

therefor operated by the movement of the planer, a feed motor, means whereby the feed motor is energized for the same direction of rotation when the reversing switch is operated and the speed of the main motor reaches a predetermined value, means whereby successive operations of the feed motor cause alternate feeding and ratcheting operations, and means for stopping the feed motor after it has made a predetermined number of revolutions, 20

In testimony whereof, I have hereunto set my hand this 22nd day of April, 1915.

JOHN EATON.
